UNITED STATES PATENT OFFICE.

ANTHONY K. ZAWADZKI, OF SAN FRANCISCO, CALIFORNIA.

SWIMMING APPARATUS.

1,221,950.

Specification of Letters Patent. Patented Apr. 10, 1917.

Application filed July 5, 1916. Serial No. 107,549.

To all whom it may concern:

Be it known that I, ANTHONY K. ZAWADZKI, a citizen of the United States, residing in the city and county of San Francisco and State of California, have invented new and useful Improvements in Swimming Apparatus, of which the following is a specification.

This invention relates to an apparatus, which is especially designed to assist swimmers, and to increase the means of propulsion through the water.

It consists in the application to the hands and feet, of flexible and extensible webs of elastic material, by which the effective surfaces of said members may be greatly extended, with a corresponding increase in the effective means of propulsion.

It also consists of details of construction, all of which will be more completely explained by reference to the accompanying drawings, in which—

Figure 1 is a view of the device adapted to the hand and partially extended.

Fig. 2 is a section on line 2—2, Fig. 1.

Fig. 3 is a section on line 3—3 of Fig. 4.

Fig. 4 is a plan of the part shown in Fig. 3.

In carrying out my invention I make coverings A adapted to fit and be worn upon the hands. These coverings are preferably of very thin and elastic rubber, which will cling and form a close fit and may have securing means at the wrists. Between the fingers of the glove, webs 2 of thin elastic material extend, and occupy this space. These webs are extended between the backs of the fingers and thumb as shown, and thus form channels 3 between the fingers, said channels having a depth equal to the thickness of the fingers from front to back. By extending the web along the backs of the fingers and to the rear of the finger crotches and between the knuckles of the hand, the channels between the fingers will be lengthened, and form pockets 4 at the inner ends of the channels, consequently when the hands are extended for a stroke and the fingers spread apart, there will be formed deep convergent channels, terminating in pockets which will receive and retain the water and assist the action of paddling.

A toe piece 6, of flexible elastic material is slipped over the front part of the foot and held in place by cords or straps 7 passing around the ankle, and a pocket 8 is formed

which opens outward to admit water when the leg is extended. The effective pressure is thus materially increased, and added to that developed by the arms. To produce the full effectiveness of these webs, the outer ends are arched or convexed as shown at 2a.

It will further be noted, that the appliance worn by either limb, *i. e.*, leg or arm, presents a channel extending longitudinally of the foot or hand respectively of the limb, and consequently in the direction of the swimming stroke, so that the pockets 4 face the direction of the effective or swimming stroke.

Having thus described my invention, what I claim and desire to secure by Letters Patent is—

1. A swimming appliance composed of a member formed for wear on a limb of the body, said member having a channel diverging at its outer end and which in swimming position extends lengthwise of the member borne by the limb and terminating at its inner end in a water trapping pocket which pocket faces in the direction of the swimming stroke and is of a width substantially equal to that of the inner end of the channel.

2. A swimming appliance composed of a member formed for wear over the toes of the foot, and a channel formed on said member and extending longitudinally of the foot and over the toes thereof in normal position of the latter and under the toes in swimming position thereof, said channel being closed at its inner end and flaring from its said inner end outwardly to form a relatively large entrance to the channel.

3. A swimming appliance composed of a member formed for wear over the toes of the foot, and a channel formed on said member and extending longitudinally of the foot and over the toes thereof in normal position of the latter and under the toes in swimming position thereof, said channel being closed at its inner end, and a member extended out beyond the channel bottom and extending beyond the toes.

In testimony whereof I have hereunto set my hand in the presence of two subscribing witnesses.

ANTHONY K. ZAWADZKI.
